FRIEDRICH HARTH, OF BAMBERG, GERMANY, ASSIGNOR TO LOUIS HARTH, OF CHICAGO, ILLINOIS.

FLYING MACHINE.

Application filed July 26, 1922. Serial No. 577,610.

To all whom it may concern:

Be it known that I, FRIEDRICH HARTH, a citizen of the Republic of Germany, residing at Bamberg, in the Free State of Bavaria and Republic of Germany, have invented 5 new and useful Improvements in Flying Machines, of which the following is a specification.

This invention relates to an aerial vehicle 10 having carrying planes which are movably supported so as to adapt themselves to the currents of air or wind and in which an alteration in its position relatively to the ground, ascent or descent, is attained by inclining the elevator rudder simultaneously 15 in the same direction as the main carrying plane.

The object of the invention is to make the planes movable to such an extent that the 20 most favorable adjustment for flying is attained in the several parts of the planes and that simultaneously the equilibrium is retained.

The invention also has the object to adjust 25 the elevator in the same sense as the carrying planes and to effect thereby ascent or descent by utilization of the wind. In this way the invention aims at utilizing the energy of the wind in the same way in 30 which this energy is utilized by a soaring bird effecting in this way a saving in the power of the engine or even permitting to eliminate the engine if the current of air is sufficiently strong.

Carrying planes are already known in 35 connection with aerial vehicles in which the two halves of the planes are mounted so that they can be inclined in the same direction or in opposite directions, or in which 40 the halves of the planes may be inclined about a transverse axis in such manner that the planes remain in fixed position with respect to the body of the aeroplane at their central portion, or in which the two halves 45 of the planes upon inclination of the planes remain rigid in themselves.

In order to alter the effect of the carrying 50 surfaces attempts have been made to vary the cross-sectional area or contour simultaneously with the inclination of the planes. It is also already known to incline the main carrying planes and the elevator rudder in the same direction for the purpose of reducing the head resistance 55 as much as possible in the ascent

if this ascent is effected by propellers alone. This simultaneous inclination of carrying planes and elevator rudder in the same direction also has been proposed for the purpose of utilizing both of these planes as 60 sails when the vehicle is on the water.

The object of the arrangements mentioned above is principally the maintenance of stability in longitudinal and transverse direction. These arrangements also have the 65 object of varying the carrying or lifting power or effecting altitude steering by varying the angle of incidence. If however, the main object is to be the adaptability of the carrying planes to the currents of air and if 70 the main object is furthermore simultaneously to facilitate easy manipulation of the planes, the arrangements described above as known are not sufficient. The mere inclination of a rigid carrying plane about 75 a transverse axis is not sufficient for the reason that the wind conditions may be different on the two sides of the vehicle. An inclination of the halves of the wings also is not sufficient as long as these halves of the 80 wings or planes remain rigid in themselves. A sufficient adaptability cannot be attained by inclination of the planes as long as the planes remain in fixed position at their central portions. If, on the other hand, 85 devices are employed to move the central portion of the planes and thus requiring special manipulation by hand, the entire device loses its practical usefulness.

Referring now to the difference in the 90 currents of air at the ends of the planes, it will be seen that a mere fixed twisting of the carrying planes also will not suffice for the requirements of adaptability. Furthermore if the axis of rotation of the planes is arranged so that it is parallel to the entire 95 length of the pressure line, easy and continuous manipulation of the planes during high wind is impossible because in adjusting the planes this pressure line is thrown suddenly from the front to the rear of the axis of rotation, or vice versa. Finally also it is not sufficient to adjust the elevator in that way in which it is usually adjusted in aeroplanes, if altitude steering is to be effected 100 by utilization of the wind.

Conforming to the purpose of adaptability of the carrying planes the present invention aims at imparting to the carrying planes a direct acting and increased move- 110

bility within wide limits. For this purpose the carrying planes were deprived of any fixed motion and rigidity as far as possible.

The invention also aims at a construction in which those portions of the planes adjacent to the body of the vehicle can be inclined in a different degree than the main supporting planes, and this difference in inclination has been introduced for reasons of stability and adaptability. The invention also provides means for inclining the elevator in the same sense as the carrying planes in order to cause thereby ascent or descent from any given position in the air by using the wind, whereby also for the purpose of retaining stability, the extent to which the elevator rudder is inclined in the same direction as the carrying planes can be varied relatively to the carrying planes.

Other objects of the invention will appear in the following detailed description taken in connection with the accompanying drawings wherein:

Fig. 1 is a fragmentary perspective view of an aeroplane constructed in accordance with this invention.

Fig. 2 is a fragmentary perspective view of a modified form of the invention.

Fig. 3 is a diagrammatic view showing in solid and dotted lines different positions of the carrying planes.

Fig. 4 is a detail view of a modified form of the control lever structure.

Fig. 5 is a diagrammatic view in perspective of the rudder mechanism and its control lever.

Fig. 6 is a detail elevation showing the lever connection with the rudder when in active position.

Fig. 7 is a detail elevation showing the lever connection with the rudder when in neutral position.

Fig. 8 is a side elevation of the operating levers showing only the rudder connections associated therewith.

In Figure 1 the carrying plane consisting of one continuous wing is movably supported in the points *a* and *b*. For the purpose of starting the inclination and for the purpose of adjusting the two halves of the carrying surface in opposite directions three cables *S*¹, *S*² and *S*³ are provided. These cables are guided over the sheaves *r*¹, *r*², *r*³ etc. up to *r*¹⁰ in the following way: Cable *S*¹ is associated with the left half of the carrying plane. It is fixed in the point *c* and is guided over the rollers *r*¹ and *r*² to the point *d* at which it is fixedly attached again. In a similar way the cable *S*² associated with the right half of the carrying plane is fixed at *e* and guided over the rollers *r*³ and *r*⁴ to the fixed point of attachment *f*. The cable *S*³ is associated with the central portion of the carrying plane and is constructed as an endless cable. It is guided over the rollers

*r*⁵, *r*⁶, *r*⁷ and *r*⁸ disposed on the body of the vehicle and over the rollers *r*⁹ and *r*¹⁰ on the carrying plane. The cables *S*¹, and *S*³, and *S*² and *S*³ respectively are quite close to each other for a short stretch at the body of the vehicle and in this part where they are adjacent to each other they are associated with two control levers *H*¹ and *H*² with which they are fixedly connected. Each of these control levers *H*¹ and *H*² is associated in a known way with one half of the carrying planes. The control levers have their fulcrums at *D*¹ and *D*² and may be moved independently of each other either both forwardly or both rearwardly or either one forwardly and the other one rearwardly.

The operation of this device is now as follows: If the two control levers *H*¹ and *H*² are simultaneously moved in opposite directions, the central cable *S*³ will simply run over its rollers and will leave the central portion of the carrying plane uninfluenced in its position. On the other hand, the cables *S*¹ and *S*² will be pulled through this movement of the levers in opposite directions and will therefore twist the entire surface of the carrying plane from the central portion out over the entire length thereof.

Depending upon the extent of inclination of one lever as compared with the opposite lever the two halves of the carrying plane also will follow this turning or twisting movement to a different degree, whereby therefore the entire carrying surface may be twisted from any cross-section. For instance one of the levers *H*¹ may be locked in any desired position while only the lever *H*² will be moved forward or back. Then the point *c* and *d* will remain stationary and from a cross-section containing these points the carrying surface will be twisted gradually up to a cross-section containing the points *e*, *f*. Naturally the opposite movement also may be imparted to the carrying surface.

If, however, the control levers are moved both in the same direction either forward or back, the cables *S*¹ and *S*² will impart a movement to both of the halves of the carrying plane in the same direction. Furthermore the central portion of the carrying plane tensioned by the cable *S*³ will follow this movement in the same direction, but to a different extent. This means that the entire carrying surface is rocked or swung about a transverse axis containing the points *a*, *b* and the inclinations of the two ends of the carrying planes or aerofoils are different from that of the central portion. This difference in the inclination of the different portions is due to the peculiar arrangement of the cables and forms an essential part of the present invention. The reason for the difference in variation of inclination of the

central part with respect to that of the ends of the plane is to be seen in this that the cable S^3 exerts a pull upon the plane more in vertical direction while the cables S^1 and S^2 engage the ends of the plane under an acute angle. Hence under normal conditions the inclination of the central portion of the plane will always be smaller than that of the outer ends. Figure 3 of the drawings shows diagrammatically the front portion or edge of the carrying plane in the normal position I and it shows this portion in dotted lines in the position II which is the position occupied by the edge if the cables S^1 and S^2 as well as S^3 are moved the same distance α and in the same direction by means of the levers.

In order to provide for the possibility of regulating the inclination of the central portion of the plane as desired, a second pair of levers H^3 may be provided in addition to the main levers H^1 and H^2 . These auxiliary levers H^3 have their fulcrums at D^3 . The fulcrums D^3 are staggered with respect to the other fulcrums, as shown in Figure 4 of the drawings, and the levers engage at their lower ends the cables S^3 while the cables S^1 and S^2 remain in engagement with the lower ends of the main levers H^1 and H^2 as shown diagrammatically in Fig. 4. The fulcrums of the levers H^3 being higher above the cable S^3 than the fulcrums of the main lever H^1 and H^2 it is obvious that the lower ends of the levers H^3 , will travel over a longer path than the other levers and will therefore exert more of a pull or tension on the central cable S^3 than on the cables S^1 and S^2 . The result of this arrangement is that the central portion of the carrying plane may be inclined differently from the outer ends of the carrying plane depending upon the fulcrums D^3 . It is also possible to arrange these fulcrums adjustably and to effect thereby a relative variation of the central portion at any desired instant.

The operation of the control levers H^1 and H^2 may also take place in such a way that one lever is moved to a larger extent than the other so that the right half or the left half of the carrying plane takes a corresponding share of the total inclination which amounts to a variable twisting or warping of the entire plane from a certain cross section.

Instead of effecting the desired inclination of the carrying plane by means of cables, it is also possible to do this by torsion tubes and lever transmission combined with a differential, as shown diagrammatically in Figure 2. The carrying planes may be moved by the torsion tubes T^1 and T^2 with the pertaining levers H^1 and H^2 or the levers h^3 and h^4 respectively. The latter, therefore, are connected with the

main control levers H^1 and H^2 by rigid bars or rods S^1 and S^2 , the levers H^1 and H^2 having their fulcrums at D^1 and D^2 . For the purpose of effecting the movement of the portions of the carrying plane near the body the differential F is provided which is also moved by the rods S^3 and S^4 from the main levers H^1 and H^2 .

Upon operating both of the main levers in the same direction the central portion of the carrying plane is moved in a different degree since the ratio of transmission for the differential is different from that for the torsion tubes. This ratio of transmission may be varied as desired by altering the point at which the rods engage the levers. If the control levers, however, are moved in opposite direction, the differential rocks about the point D^3 which is located at the front spar and in this way the central portion of the carrying plane is left motionless. In the same way all of the other movements may be effected as have been described above when cables are employed.

The described arrangements produce the result that the right half of the carrying plane and the left half may be moved independently of each other into that position which is the most favorable position with respect to the wind, and furthermore, that upon inclining the entire surface of the carrying plane each portion of the carrying plane may receive that position which is most favorable with respect to the wind, whereby the required adaptability of the carrying plane for soaring by utilizing wind energy may be attained, and whereby furthermore, at the same time all of the requirements for maintaining stability are complied with.

The adjustment of the carrying planes as effected by the arrangement described, takes place about an axis which is located at an angle to the entire pressure line. Ordinarily, therefore, the front edge of the carrying surface and the axis of rotation will not be parallel to each other. Normally the axis of rotation will cross the carrying plane at an angle.

The effect of this arrangement is that upon changing the inclinations of the carrying planes the pressure line is not shifted suddenly or in jerks between the front and the rear of the axis of rotation, thus resulting in excessive stresses due to the control, but this shifting of the pressure line is effected gradually when changing the inclination.

This arrangement, furthermore has the advantage that the strains due to the controlling movements remain within moderate limits and that a stable inclination of the carrying plane may be effected quite easily in a strong wind.

The movable elevator rudder J is connected by means of the cables S^4 and S^5 with the main levers H^1 and H^2 in such manner that this rudder may be inclined 5 in the same direction as the carrying surface and that it may remain in neutral position while at the same time the carrying plane undergoes some movement. The arrangement, furthermore, provides for the 10 possibility of varying the degree of inclination of the elevator rudder with respect to the inclination of the carrying surface. Fig. 5.

The purpose of this arrangement is to effect 15 an ascent by utilizing the wind only without using motor power, or to make the ascent in a more rational way. By adjusting the elevator of an aeroplane without motive power in the conventional way, that is negative when ascending, a rational ascent with the aid of wind is impossible. In fact the aeroplane will slide back. If, however, the main carrying surface and the elevator are inclined in the same direction positively, 20 the effect will be that not only the front portion of the body but also the rear end of the body are lifted. In this way an ascent is possible by utilizing the wind only. If both of these surfaces are adjusted negatively, 25 rapid descent may be attained in about the same way as can frequently be observed in birds.

In order to attain this desired adjustment the following arrangement is made. The 30 controlling cables S^4 and S^5 , Fig. 5, are adjustably connected with the levers H^1 and H^2 at the points g , h , i , k by sliding sleeves G^1 and G^2 and set screws S^9 or any other suitable means. The controlling cables are 35 guided parallel to each other and therefore, can be operated parallel to each other or their points of engagement may be brought together with the fulcrums D^1 and D^2 as indicated in Fig. 7 of the drawings, 40 of the main levers H^1 and H^2 in which latter case the elevator J is retained in an indifferent or neutral position. In order to leave the elevator uninfluenced when operating the levers H^1 and H^2 in opposite directions for the purpose of twisting the main carrying plane, the cables S^4 and S^5 are guided in a known way over the pulleys r^{11} and r^{12} . Figure 5 shows diagrammatically 45 this control of the elevator rudder. Figures 50 6 and 7 show the two extreme possibilities of the cable control. The adjustability of the points of attachment is attained by the arrangement illustrated in Figure 8. The ends of the cables S^4 and S^5 are secured to the slides 55 G^1 and G^2 which are movable on the slide bars K^1 and K^2 . The slides are connected with each other in some suitable way, as for instance, by the endless cord S^6 which is guided over the pulleys r^{13} and r^{14} . The 60 slide G^1 furthermore is connected with a slid- 65

ing handle L on the hand lever H^1 through a connecting rod N . The lever H^2 has the same construction as shown in Figure 8.

The arrangement as shown in Figure 8 operates in the following way: If the handles L are moved to their uppermost position the slides G^1 and G^2 are moved away from each other and the cables take a position as shown in Figure 6. If, however, the handles L are lowered the slides G^1 and G^2 are moved towards each other that is up to the fulcrums of the levers H^1 and H^2 . The controlling cables are then in a neutral position as shown in Figure 7. Under normal conditions of flight 70 these controlling cables will occupy the last named position, Fig. 7, in which position the gusts of wind are in the main caught by the principal carrying surface. The elevator then performs the function of a directing 75 surface only. If, however, altitude steering is desired then the controlling cables S^4 and S^5 are moved into the position as shown in Figure 6, by pushing the handles L upward 80 on the levers H^1 and H^2 . The cables are then in parallel and the elevator can only be inclined in the same sense as the main supporting planes. If it is desired to fly 85 higher, both of these surfaces will be adjusted positively; if it is desired to descend 90 both of them will be adjusted negatively. It is also possible through partly lowering 95 or raising the handles L to adjust the degree of movement of the elevator. Contrary 100 to the conventional method of steering, ascending and descending as herein described amounts to rising and falling of the aerial vehicle with reference to its front part and tail end.

The rudder may be controlled in a known 105 way by pedals.

The invention is primarily intended for a monoplane having a carrying surface supported by a cantilever spar on which the ribs are arranged in such a manner that same can be moved by cables fastened to two main ribs c , d , and e , f . This arrangement may also be used for other carrying surfaces as well as for biplanes or for aeroplanes with more than two superposed carrying surfaces. Instead of utilizing controlling cables or torsion tubes other means for transmitting the control may be used.

It is, of course, to be understood that the invention may be constructed in other manners and the parts associated in different relations and therefore, I do not desire to be limited in any manner except as set forth in the claims hereunto appended.

Having thus described my invention what I claim is:

1. In aircraft for utilizing air currents for motive power, a fuselage, an aerofoil, levers, and means connecting said levers and aerofoil for changing the form of the aero- 130

- foil by warping and inclining it to an equal degree on each side of the fuselage and at a different degree at the transverse center of the aerofoil.
- 5 2. In aircraft for utilizing air currents for motive power, a fuselage, an aerofoil, levers, and means connecting said levers and aerofoil for changing the form of the aerofoil by warping and inclining it to an equal degree on each side of the fuselage and at a different degree at the transverse center of the aerofoil, said means adapted to warp and incline front or rear portions of aerofoil in the same or opposite directions.
- 10 3. In aircraft for utilizing air currents for motive power, a fuselage, an aerofoil pivotally supported from the fuselage to permit inclining of the front or rear edge of the aerofoil, levers, and means connecting said levers and aerofoil for changing the form of the aerofoil by moving the center and each end at different transverse angular degrees with respect to each other.
- 15 4. In aircraft for utilizing air currents for motive power, a fuselage, an aerofoil pivotally supported from the fuselage to permit inclining of the front or rear edge of the aerofoil, levers, and means connecting said levers and aerofoil for changing the form of the aerofoil by warping and inclining it to an equal degree on each side of the fuselage, and at a different degree at the transverse center of the aerofoil.
- 20 5. In aircraft, a fuselage, an aerofoil, levers, means connecting said levers and aerofoil for changing the form of the aerofoil by warping and inclining it to an equal degree on each side of the fuselage, and at a different degree at the transverse center of the aerofoil upon equal movement of the levers in the same direction, said means arranged whereby upon equal movement of said levers in opposite directions the transverse center of the aerofoil will remain unaffected.
- 25 6. In aircraft for utilizing air currents for motive power, a fuselage, an aerofoil pivotally supported from the fuselage to
- permit inclining of the front or rear edge of the aerofoil, levers, and means connecting said levers and aerofoil for changing the form of the aerofoil by warping and inclining it to an equal degree on each side of the fuselage, said aerofoil being distorted along an axis extending at an oblique angle to the line of pressure against the aerofoil.
- 30 7. In aircraft for utilizing air currents for motive power, a fuselage, an aerofoil, levers, means connecting said levers and aerofoil for changing the form of the aerofoil by warping and inclining it to an equal degree on each side of the fuselage, and a second set of levers for changing the degree of inclination of the transverse central portion of the aerofoil.
- 35 8. In aircraft for utilizing air currents for motive power, a fuselage, an aerofoil, levers, means connecting said levers and aerofoil for changing the form of the aerofoil by warping and inclining it, an elevator mounted to be inclined parallel to the inclination of the aerofoil, control cables connected to said elevator and said levers, and means for adjusting the relative positions of the connection between the cables and levers and the fulcrum of the levers to vary the operating range of the elevator.
- 40 9. In an aircraft adaptable for utilizing air currents, a fuselage, and an aerofoil pivotally supported from the fuselage and means for warping the aerofoil along an axis extending at an oblique angle to the line of pressure against the aerofoil.
- 45 10. In air craft for utilizing air currents for motor power, fuselage, an aerofoil pivotally supported from the fuselage, levers and means connecting said levers and aerofoil for changing the form of the aerofoil by independently warping each end thereof from any point along the aerofoil or any point outside the aerofoil to degrees of different angles with respect to each other.

In testimony whereof I affix my signature.

FRIEDRICH HARTH.
